UNITED STATES PATENT OFFICE.

GUY H. BLACKSTONE, OF ZANESVILLE, AND ROBERT E. SILVEY, OF COLUMBUS, OHIO.

DESIGN FOR A COMBINATION DRESSING TABLE AND WARDROBE.

Application filed October 27, 1924. Serial No. 11,197. Term of patent 3½ years.

To all whom it may concern:

Be it known that we, GUY H. BLACKSTONE, a citizen of the United States, and a resident of Zanesville, in the county of Muskingum and State of Ohio, and ROBERT E. SILVEY, a citizen of the United States, and a resident of Columbus, in the county of Franklin and State of Ohio, have invented a new, original, and ornamental Design for Combination Dressing Tables and Wardrobes, of which the following is a specification, reference being had to the accompanying drawing, forming part thereof.

We claim:

The ornamental design for a combination dressing table and wardrobe, as shown.

GUY H. BLACKSTONE.
ROBERT E. SILVEY.
